DRAWER PULL

Earl M. Borchers, Rockford, Ill., assignor to American Cabinet Hardware Corporation,
Rockford, Ill., a corporation of Illinois

Application April 18, 1952, Serial No. 19,395

Term of patent 14 years

(Cl. D10—8)

To all whom it may concern:

Be it known that I, Earl M. Borchers, a citizen of the United States, residing at Rockford, in the county of Winnebago and State of Illinois, have invented a new, original, and ornamental Design for a Drawer Pull, of which the following is a specification, reference being had to the accompanying drawing, forming a part thereof.

Figs. 1 and 2 are respectively side and front elevational views of a drawer pull embodying my new design.

Fig. 3 is an end view on an enlarged scale.

Fig. 4 is a sectional view on line 4—4 of Fig. 2, also on an enlarged scale.

I claim:

The ornamental design for a drawer pull, substantially as shown.

EARL M. BORCHERS.
